UNITED STATES PATENT OFFICE.

PAUL W. DILLON, OF STERLING, ILLINOIS.

MECHANISM FOR GASOLENE-ENGINES.

No. 879,609.

Specification of Letters Patent.

Patented Feb. 18, 1908.

Application filed December 22, 1905. Serial No. 292,898.

To all whom it may concern:

Be it known that I, PAUL W. DILLON, a citizen of the United States, residing at Sterling, in the county of Whiteside and State of Illinois, have invented certain new and useful Improvements in Mechanism for Gasoline-Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention has reference to mechanism for gasoline engines, and pertains more especially to those devices by means of which the successive charges of gas are generated and exploded.

One of the chief improvements in my invention consists in means for holding each charge of gas under pressure and exploding it, the force of the explosion opening means of communication to the cylinder of the engine. Provision is also made for a partial reduction of the expansive force before it comes in contact with the piston-head.

In the drawings: Figure 1 is a vertical longitudinal section in the line $x-x$ of Fig. 3. Fig. 2 is an enlarged detail showing the pump mechanism. Fig. 3 is a plan view, with the cylinder mechanism in partial section. Fig. 4 is an enlarged detail, partly in section in the line $y-y$ of Fig. 3. Fig. 5 shows the cam 50 in enlarged detail, and Fig. 6 is a similar view of the cam 57.

Similar numbers refer to similar parts throughout the several figures.

1 represents a receptacle, divided by a partition 2 into the compartments 3 and 4, the chamber 3 constituting a storage tank for the hydrocarbon which furnishes the explosive charge. The chamber 3 is provided with a supply pipe 5, and an outlet pipe 6 leading to a small chamber 7. The chamber 4 is intended for the storage of air under pressure, such chamber being provided with an outlet pipe 8, connecting with the chamber 9, just below the chamber 7. Communicating with the compartment 9 is an explosion chamber 10, and above the last-named chamber, and communicating therewith, is a chamber 11. Inclosing the compartments 7, 9, 10 and 11 is a casing 12.

The passage from the compartment 9 to the explosion chamber 10 is adapted to be

closed by an upwardly seating valve 13, supported on the lower end of a valve-stem 14, which is projected upwardly through and above the compartment 9. The passage 60 from the chamber 10 to the chamber 11 is provided with a downwardly seating valve 15, fixed on the lower end of a valve-stem 16, which is projected upwardly through and above the casing 12. In the floor of the 65 chamber 7 is a small opening 17, forming means of communication between such chamber and the compartment 9, said opening being normally closed by a needle-valve 18, extending upwardly through the chamber 7, 70 and provided above the same with a valve-stem 19.

The explosion chamber 10 is provided with a sparking device 20, which can be operated in any usual manner to ignite the 75 successive charges of gas in such chamber.

21 is a rotary shaft on which is fixed a rotary piston-wheel 22, provided on its periphery with a series of equi-distant blades or pistons 23. Inclosing the blades 23 is a 80 casing 24, there being formed by such casing and the periphery of the wheel 22 a rotary cylinder 25. At one portion of its periphery the casing 24 is attached to the casing 12, and the compartment 11 communicates with 85 the cylinder 25 through a passage 26. The cylinder 25 is provided with an exhaust pipe 27.

In Fig. 3 is shown a rotary shaft 28, supported at right angles to the shaft 21 by means of a bearing 29 on said last-named 90 shaft and a journal box 30 on the opposite end of the shaft 28, such box being supported on a suitable frame or bed. (Not shown.) Feathered on the shaft 28 is a friction-wheel 31, engaged by a friction disk 95 32 fixed on the shaft 21. Integral with the wheel 31 is a collar 33, engaged by the lower forked end of a lever 34, which may be fulcrumed in the frame of the machine (not shown) so that by the operation of such lever 100 the wheel 31 can be adjusted upon the shaft 28, with reference to the disk 32.

Fixed to the casing 24 is a bracket 35, perforated to permit the passage of the upper ends of the valve-stems 14, 16 and 19, respectively. A pair of supports 36 are secured to the casing 12, and fixed in such supports is a stationary shaft 37. Fulcrumed on the shaft 37 is a lever 38, provided at one end with a yoke 39, engaging a collar 40 on 110 the valve-stem 16. On the shaft 28 is fixed a cam 41, having in one of its faces a cam-

track 42, engaged by a roller 43 (dotted lines) on the end of the lever 38. Interposed between the bracket 35 and collar 40, on the valve-stem 16, is an extensile coiled spring 44, and a similar spring 45, of less tension than that of the spring 44, is secured on the upper end of the stem 16, between the bracket 35 and a collar 46 on the upper end of the valve-stem. A lever 47 is also fulcrumed on the shaft 37, and is provided at one end with a yoke 48, engaging a collar 49 on the valve-stem 14. A cam 50 is fixed on the shaft 28, provided in one of its faces with a cam-track 51, engaged by a follower 52 (dotted lines) on the end of the lever 47. An extensile coiled spring 53 is secured between the bracket 35 and a collar 53^a on the upper end of the valve-stem 14. A lever 54 is also fulcrumed on the shaft 37, and provided at one end with a yoke 55 engaging a collar 56 on the valve-stem 19. On the shaft 28 is fixed a cam 57, having in one of its faces a cam-track 58, engaged by a follower 59 (dotted lines) on the end of the lever 54. Interposed between the bracket 35 and collar 56, on the valve-stem 19, is an extensile coiled spring 60.

61 is an air-pump, provided with a plunger 62, connected by a pitman 63 with a crank 64 on the end of the shaft 28. By means of a pipe 65 the air is forced from such pump into the chamber 4, and from thence through the pipe 8 to the compartment 9. The pipe 65 is provided with a check-valve, as at 66, to prevent the return of the air to the pump, and said pump has an inlet pipe 67; provided with a suitable check-valve to prevent return of the air through such pipe. To equalize the pressure of the air and gases in the tanks 3 and 4, such tanks are connected by a pipe 68. The shaft 21 is journaled in bearing 69, suitably supported on a foundation or frame. (Not shown.)

The style of engine shown in the drawings is especially adapted for use in connection with motor-vehicles, in which use the movement of the shaft 21 would be imparted by any suitable method to the rear axle of the vehicle. When used in this way the bearings 69 and 30 would be secured to the body or frame of the motor-car, and the lever 34 adapted to be operated from the front of the vehicle.

The operation of the machine is as follows: Assuming the air in the tank 4 to be under pressure, the valve 18 is raised sufficiently to permit a small quantity of gasoline to run into the compartment 9, where it is mixed with a sufficient quantity of air to produce the necessary charge of gas. The valve 13 is then opened by the operation of the cam 50, the action of which raises the outer end of the lever 47, causing the inner end thereof to force the collar 49 and valve-stem 14 downwardly, opening the valve. The charge of gas then passes from the compartment 9 into

the chamber 10, and the valve 13 is again closed, such valve being normally held in a closed position by means of the spring 53. Upon the closing of the valve 13 the charge in the chamber 10 is ignited and the explosion follows. The valve 15 is normally held in position in the valve-seat by means of the spring 44, the tension of which is sufficient to resist the pressure of the gas in the chamber 10 before it is ignited. The force of the explosion, however, opens the valve 15, and permits the gas to expand into the compartment 11, and from thence through the passage 26 into the cylinder 25. The angle of the passage 26 with reference to said cylinder is such as to cause the escaping gases to strike against the rear faces of the vanes 23 at approximately a right angle, the force of each explosion being expended upon a plurality of such vanes. The purpose of the compartment 11 is to permit a partial expansion of the gas, immediately following the explosion resulting in a steadier movement of the wheel 22. Were it not for the interposition of such compartment the force of the explosion would be imparted directly to the pistons, and would be in the nature of a blow, whereas the use of the chamber 11 gives to the force of the gases the effect of a push.

When the force of the explosion has been expended the yoke 39 is again moved downwardly, permitting the valve 15 to return to its seat. To prevent such valve moving downwardly and seating too abruptly the spring 45 is provided on the upper end of the valve-stem. The tension of this spring is not sufficiently strong to counteract the force of the spring 44, but prevents a too sudden impact of the valve with the valve-seat. After entering the cylinder 25 the gases pass nearly around the wheel 22, escaping through the exhaust-pipe 27. After being set in motion the explosions follow one another in rapid succession, and the movement of the wheel 22 and shaft 21 becomes continuous.

The speed of the operating devices, and consequent speed of the engine, can be varied by adjustment of the wheel 31 upon the shaft 28. If such wheel is engaged by the disk 32 near the center of such disk, as shown in Fig. 3, the speed of said wheel, and of the devices controlled thereby, will be at a minimum, but as the wheel is moved toward the periphery of the disk, such speed will correspondingly increase. Through the rotation of the shaft 28 the pump 61 is continuously operated to maintain the air pressure in the tank 4.

While the drawings illustrate my device in connection with a rotary engine, I do not wish to be understood as limiting myself to that construction, as by slight adaptation the same mechanisms can be easily applied to engines of other types.

In some devices of this class the explosive charge is first compressed and then conducted to a chamber communicating with the cylinder of the engine, where the explosion takes place. In doing this the charge expands to some extent before the explosion, and the effect of the compression it has been subjected to is in some degree lost. The efficiency of the explosion is increased by 5 the degree of pressure to which the charge is subjected just prior to the explosion, and in my machine it is designed to maintain the same pressure upon the gas in the chamber 10 as before it enters such chamber, and 10 there being no opportunity for the gas to expand or escape until the explosion takes place the charge of gas remains under the same pressure until that time.

What I claim as my invention, and desire 20 to secure by Letters Patent of the United States, is:

1. Mechanism for gasolene engines, comprising a rotary shaft 21, provided with a disk 32, fixed thereon; a rotary shaft 28, at 25 right angles to the shaft 21, and having a friction wheel 31 slidably mounted thereon; a wheel 22, fixed on the shaft 21, and provided on its periphery with a plurality of vanes; a circular casing, inclosing said vanes; 30 an expansion chamber, communicating with said cylinder; an explosion chamber, communicating with said expansion chamber; a valve, closing the opening between said explosion and expansion chambers; means for 35 holding such valve normally closed; means for holding said valve open immediately following the explosion, such means being actuated by the rotation of the shaft 28; a mixing chamber, communicating with said explosion chamber, and provided with a valve 40

adapted to close the opening between the same; means for holding such valve normally closed; means for suitably opening such valve by each rotation of the shaft 28; an oil chamber, communicating with said mixing chamber, and provided with a valve normally closing the opening between the same; means for holding such valve normally closed; means for slidably opening such valve upon each rotation of the shaft 28; means for introducing a current of air under pressure to the mixing chamber; and means for adjustment of the wheel 31 upon the shaft 28, substantially as shown and described. 45

2. In mechanism of the class named, the 55 combination of the explosion chamber 10; the expansion compartment 11, auxiliary thereto; the valve 15, interposed between the chambers 10 and 11, and provided with the valve stem 16; the spring 44, holding the 60 valve 15 normally in its seat; the lever 38, engaging the valve-stem 16 to hold said valve open, and means for suitably actuating the lever 38, substantially as shown and described. 65

3. The combination of the chamber 9, provided with the outlet valve 13; the valve-stem 14, fixed to the valve 13, and provided with a collar 49; the spring 53, holding the valve 13 normally in its seat; lever 47, engaging the collar 49; and means for suitably actuating said lever, substantially as and for 70 the purpose set forth.

In testimony whereof, I affix my signature, in presence of two witnesses.

PAUL W. DILLON.
